R. L. LUND.

DRIER.

APPLICATION FILED FEB. 4, 1918.

1,318,780.

Patented Oct. 14, 1919.

UNITED STATES PATENT OFFICE.

ROBERT L. LUND, OF ST. LOUIS, MISSOURI.

DRIER.

1,318,780.

Specification of Letters Patent. Patented Oct. 14, 1919.

Application filed February 4, 1918. Serial No. 215,303.

To all whom it may concern:

Be it known that I, ROBERT L. LUND, a citizen of the United States of America, a resident of the city of St. Louis, State of Missouri, have invented certain new and useful Improvements in Driers, of which the following is a full, clear, and exact description, reference being had to the accompanying drawing, forming a part of this specification.

My invention relates to improvements in driers, and more specifically stated to a heating device adapted for use in drying shoe soles for whatever purpose it may be necessary.

One of the objects of the invention is to provide a simple and efficient means whereby articles, such as shoe soles, can be quickly and thoroughly dried without the danger of overheating the articles and without scratching or otherwise marring them. Another object is to enable the shoes to be easily and quickly positioned on the drier, thereby saving considerable time in drying large numbers of shoes, and at the same time enabling each shoe to be properly positioned relative to the heating element.

With the foregoing and other objects in view, the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Figure I is a top or plan view of a drier constructed in accordance with the invention, a portion of one of the pads or seats being broken away to show the sheet metal heat transmitting member.

Fig. II is an inverted plan view of the drier.

Fig. III is an end view.

Fig. IV is a transverse section.

Fig. V shows a heating device conforming to the curvature of the shoe sole.

To illustrate the invention I have shown two drying devices A and A' arranged in the form of steps so that shoes or other articles to be dried can be easily placed upon both of the devices. Each of the devices A and A' comprises a sheet metal heat transmitting member 1 having its margins 1' turned

downwardly and inwardly (Figs. II and IV) to form a heating chamber, an electrical heating element such as resistance wires 2 arranged in said heating chamber, a sheet 60 of heat insulating material 3, preferably asbestos, arranged below the electrical heating element, and a pad 4 covering the top face of the sheet metal heat transmitting member 1. Each pad 4 is preferably a sheet of 65 felt or other suitable fabric, having its rear margin folded under and secured by means of an angle bar 5 as shown in Figs. II and IV, the front margin being folded partially around and secured by rods 6 and 7 in front 70 of the heating chamber. Cross bars 8 (Fig. II) are secured under each sheet of insulating material 3.

The ends of the drying devices A—A' are connected together by means of diagonal 75 members 9. Each drying device is also provided with a stop rod 10 arranged over its pad 4 and secured to brackets 12 which extend upwardly from the ends of the heating chamber. Each stop rod 10 is preferably 80 covered by a pad 10'. The heating element of each drying device is provided with a pair of binding posts 13 and wires leading therefrom to a switch 14, which may be operated to control the flow of electricity to 85 both of the electrical heating elements.

It will now be understood that each drying device preferably comprises an electrical heating element confined between a sheet of asbestos 3 and a sheet metal heat transmitting member 1, the latter being covered by a pad 4. The pad prevents the shoe soles from being overheated by the electrical heater, at the same time enabling the shoes to be quickly placed upon and removed from 95 the drier without scratching the bottom faces of the soles. As a further means for increasing the speed of the operator, the padded stop rod 10 is secured over the pad 4 so as to coöperate with the shoe uppers as 100 shown in Fig. IV, thereby enabling the shoes to be quickly and properly located on the pad 4. The shoe soles are quickly and thoroughly dried by the action of the heat transmitted through the pad 4 upon which the 105 soles are seated.

Heretofore, shoe soles have been dried by using a large heating chamber open at the top for the discharge of hot air to the shoes. A screen, or the like, is usually arranged 110 over the open top of the heating chamber so as to support the shoes in the course of

the rising hot air currents. The shoes are separated from each other and arranged over the heating chamber in a somewhat disorderly manner. Obviously, the rising hot air can escape freely around and between the shoes, and the action of the heat is not concentrated on the soles of the shoes. In using these earlier driers, a very large percentage of the heat is dissipated, or wasted, by passing freely from the heating chamber to the atmosphere.

In accordance with the present invention, the sheet metal heat transmitting member 1 is exposed directly to the heat generated in 15 the heating chamber and the heat is transmitted, by radiation, from the metal to the soles of the shoes. Instead of being carried away freely by rising air currents, the heat radiating from the metal is transmitted directly through the thin pad 4 to the soles of 20 the shoes. The action of the heat is thus very effectively concentrated on the soles of the shoes.

The drier produced by the combination of 25 elements herein shown is a relatively small apparatus, but it will hold a large number of shoes, arranged compactly and in an orderly manner so they can be conveniently reached by the operator.

30 In Fig. V, I have shown a heating chamber 20 having its upper portion curved to conform approximately to the curvature of the bottom face of the shoe soles. This curved portion is covered by a thin pad 21 which forms a seat for the shoes. By forming the drier in this manner the entire bottom face of the shoe sole will contact with the pad 21, and the heat will be transmitted from the pad directly to the shoe sole, 40 without having an opportunity to escape into the atmosphere.

I claim:

1. A drier comprising an electrical heating element, a heat transmitting member 45 covering said electrical heating element, a pad covering said heat transmitting member and forming a seat for the articles to be dried, and a heat insulator covered by said electrical heating element, the latter being 50 confined between said heat transmitting member and the heat insulator.

2. A shoe drier of the character described comprising a heating element, a heat transmitting member covering said heating element, a pad covering said heat transmitting member and forming a seat for the soles of the shoes to be dried, and a stop arranged over said pad to limit the movements of the shoes.

60 3. A shoe drier of the character described comprising an electrical heating element, a

heat transmitting member covering said electrical heating element, a pad covering said heat transmitting member and forming a seat for the soles of the shoes to be dried, and an elongated padded stop bar secured over said pad so as to coöperate with the uppers of the shoes in determining the positions of the shoes relative to said pad. 65

4. A shoe drier of the character described 70 comprising a plurality of shoe receiving devices arranged in a stepped relation to each other, each of said shoe receiving devices comprising a pad forming a seat for the soles of the shoes, a sheet metal heat transmitting member covered by said pad, a heating chamber being formed below said sheet metal heat transmitting member, and a heating device confined in said heating chamber. 75

5. A shoe drier of the character described 80 comprising a plurality of shoe receiving devices arranged in a stepped relation to each other, each of said shoe receiving devices comprising a pad forming a seat for the soles of the shoes, a sheet metal heat transmitting member carried by said pad, a heat insulator below said sheet metal heat transmitting member, an electrical heater confined between said pad and the heat insulator, and an elongated stop member secured over said pad to limit the movements 85 of the shoes seated on said pad, and diagonal connecting members securing the ends of each of said shoe receiving devices to the adjacent shoe receiving device. 90

6. A drier comprising a housing, an electrical heating element in said housing, a pad covering the top of said housing and forming a seat for the articles to be dried, and a stop secured above said pad to limit the 100 movements of said articles.

7. A shoe drier of the character described comprising a sheet metal heat transmitting member having its margins turned downwardly to form a heating chamber, an electrical heating element confined in said heating chamber, a pad made of sheet material covering said heat transmitting member and forming a seat for the soles of the shoes, margins of said pad being turned downwardly and secured, supporting brackets extending upwardly at the opposite ends of said heating chamber, and a stop rod arranged above said pad and having its ends secured to said supporting brackets so as to coöperate with the shoe uppers in limiting the movements of the shoes supported on said pad. 105 110 115

In testimony that I claim the foregoing I hereunto affix my signature.

ROBT. L. LUND.
